US00D594835S

(12) **United States Design Patent**
Chu

(10) **Patent No.:** **US D594,835 S**
(45) **Date of Patent:** **** Jun. 23, 2009**

(54) **MOBILE PHONE**

(75) Inventor: **Chih-Ming Chu**, Taipei (TW)

(73) Assignee: **Hannspree, Inc.**, Taipei (TW)

(**) Term: **14 Years**

(21) Appl. No.: **29/306,835**

(22) Filed: **Apr. 17, 2008**

(51) **LOC (9) Cl.** **14-03**

(52) **U.S. Cl.** **D14/138 AA**

(58) **Field of Classification Search** **D14/137, D14/138 R, 138 AA, 138 AB, 138 AC, 138 AD, D14/138 C, 138 G, 147-148, 156, 191, 218, D14/247-248, 341-347, 390, 399, 455-456, D14/496; D16/208; D21/329, 331, 333, D21/517; 348/14.01-14.02; 361/814; 379/433.01-433.13; 455/90.3, 556.1-556.2, 566, 575.1, 575.3, 455/575.4; D13/164, 168; 439/165; 343/702; 345/167, 168, 169; D10/65, 78, 104; D18/7**
